UNITED STATES PATENT OFFICE.

GEORGE E. GOUCHER, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 12,648, dated January 3, 1882.

Application filed November 28, 1881. Term of patent 14 years.

To all whom it may concern:

Be it known that I, GEORGE E. GOUCHER, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a flat tape or gimp heading, A, to which is attached at intervals a series of pendants, B, of substantially cylindrical contour, each composed of chenille threads twisted helically about the axis of the pendant and projecting loosely therefrom. The pendants B, which may be of any desired color, either uniform in tint or shaded or striped, are each ornamented by being swelled or increased in diameter from one of its ends to or about the center of its length, being thus composed of a wide section,

b, and a narrow section, *b'*, the length of the wide section *b* being consequently so much greater than the diameter of the pendant as to present an entirely different appearance or effect 25 from that of a pendant having a swelled or tufted end or center, or both.

The heading A may, if desired, be ornamented by a cord, *a*, woven into its fabric, so as to present a raised pattern upon its surface. 30

I claim—

A design for fringe, consisting of a flat tape or gimp heading and a series of pendants, each composed of a wide and a narrow section united at or about the middle of the length of the 35 pendant and extending from their point of union in opposite directions to the ends of the pendant, substantially as set forth.

GEO. E. GOUCHER.
